UNITED STATES PATENT OFFICE.

WILLIAM COOPER, OF WEST NEWTON, MASSACHUSETTS.

MICA-SPLITTING MACHINE.

1,185,881.

Specification of Letters Patent. Patented June 6, 1916.

Application filed March 23, 1916. Serial No. 86,232.

To all whom it may concern:

Be it known that I, WILLIAM COOPER, a citizen of the United States, residing at West Newton, in the county of Middlesex 5 and State of Massachusetts, have invented certain new and useful Improvements in Mica-Splitting Machines; and I do declare the following to be a full, clear, and exact description of the invention, such as will 10 enable others skilled in the art to which it appertains to make and use the same.

My invention relates to improvements in machines for splitting sheets of mica into much thinner sheets which are used commercially. The improved machine is of the class which bends the sheets of mica in order to separate the numerous layers thereof, and the object is to provide an extremely simple machine of this class employing bending 15 rollers so constructed as to gradually rather than abruptly bend the material, thus obviating all danger of cracking the same.

With the foregoing general object in view, the invention resides in certain novel features of construction and in unique combinations of parts to be hereinafter fully described and claimed, the descriptive matter being supplemented by the accompanying drawings which constitute a part of this application and in which:

Figure 1 is a central vertical longitudinal section of a machine constructed in accordance with my invention; Fig. 2 is a top plan view thereof; Fig. 3 is a vertical transverse 35 section taken on the plane of the line 3—3 of Fig. 1.

In specifically describing the construction shown in the drawings above briefly described, similar characters will be placed on 40 corresponding parts throughout the several views, and reference will be herein made to the numerous elements by their respective indices. To this end, the numerals 1 designate a pair of parallel sills from one end 45 of which a pair of bearings 2 rise, while a pair of standards 3 extend from the other ends of said sills. Mounted respectively between the bearings 2 and the standards 3 are front and rear drums 4 and 5 around which 50 an endless belt conveyer 6 of any preferred material passes, the shafts of both drums being equipped with sprockets 6' around which a sprocket chain 7 passes, while the shaft of the drum 5 is equipped with a driving pulley 8. Thus, when this pulley is 55 driven, both drums 4 and 5 will be rotated

to move the conveyer 6 in the direction of the arrow in Fig. 1, this conveyer serving to carry sheets of mica M through the machine.

Rising from the sills, between the bearings 60 2 and standards 3, are other standards 9 which are disposed in pairs, with the standards of each pair aligned transversely of the machine. As shown clearly in Fig. 1, the standards 9 decrease gradually in height 65 from the inlet end I of the machine to the outlet end O thereof, and said standards carry lower and upper ribbed rollers 11 and 12 respectively which are disposed above and below the upper reach of the conveyer 6. 70 The diameters of the rollers 11 and 12 decrease gradually from the inlet to the outlet end of the machine as shown most clearly in Fig. 1, said rollers being formed with uninterrupted longitudinal ribs 13 on their peripheries, the ribs of the upper rollers meshing with those of the lower rollers, while the upper reach of the conveyer 6 passes between the intermeshing ribs. The ribs 13 decrease 75 in size from the inlet to the outlet end of 80 the machine, while the spaces between said ribs correspondingly decrease.

The function of the ribbed rollers arranged as shown and described is to bend the sheets of mica M as they are fed through 85 the machine on the upper reach of the conveyer 6. Obviously, due to the graduated rollers and ribs, the sheets of mica will be slightly bent and will then gradually be more abruptly bent as they reach the outlet end O. 90 During this operation, it is essential that either the upper or lower rollers be allowed to yield vertically, and for allowing this movement, the bearings 14 of the upper rollers 12 are shown in the present embodiment of the invention as mounted slidably 95 in upright guideways 15 formed in the upper ends of the standards 9, coiled springs 16 being housed in said guideways above the bearings 14 to normally depress the latter. 100 The tension of the springs 16 may be varied at will by the use of set screws 17 which control the vertical positions of plates 18 against the upper ends of which the springs 16 bear, said screws being threaded through crown 105 plates 19 which close the upper ends of the guideways 15.

Passing the sheets of mica through the machine in the manner set forth, loosens the numerous layers thereof, these layers being 110 separated at the outlet end O of the machine by a rubber covered roller 20 which rotates

immediately above the drum 5, being forced toward the upper reach of the conveyer 6 by springs 21 carried in guideways 22 formed in the upper ends of the standards 5 3, it being in said guideways that the bearings 23 of said roller 20 are mounted for vertical sliding movement. The roller 20 is provided with a driving pulley 24 and is adapted to be rotated at a much higher peripheral speed than the drum 5, said roller traveling in the direction of the arrow at the left of Fig. 1. Thus, the roller 20 will slide the numerous layers of mica one upon the other and will thus effectively separate 10 said layers.

In most cases, set screws 25 will be provided for varying the tension of the springs 21 in order that the roller 20 may be held downwardly with more or less force, according 20 to the character of the mica being split.

From the foregoing, taken in connection with the accompanying drawings, it will be obvious that I have provided an extremely simple machine for accomplishing the object 25 of the invention, but that it will be highly efficient and durable. Furthermore, it is to be understood that although certain specific details have been shown and described, numerous changes may be made within the 30 scope of the invention as claimed without sacrificing the main advantages thereof.

I claim:

1. A mica splitting machine comprising a series of opposed vertical standards, a pair 35 of drums disposed one at each end of said series, one of said drums being driven, an endless belt passing around the two drums, a lower series of rollers beneath the upper reach of said belt and having uninterrupted 40 longitudinal ribs on their peripheries, said rollers being mounted between the lower

ends of the aforesaid standards, an upper series of rollers disposed above the upper reach of the belt and likewise having uninterrupted longitudinal ribs on their peripheries, the ribs of the upper and lower rollers being in mesh while said upper reach of the belt passes between said intermeshed ribs, the width of said ribs decreasing in the direction of travel of said upper reach of the belt, vertically movable bearings for the upper series of rollers and carried by the standards, means for forcing said bearings normally downward, a swiftly rotating separating roller above the delivery end of the upper reach of the belt, and means for forcing said separating roller toward said reach. 45

2. A mica splitting machine comprising a lower series of rollers having longitudinal uninterrupted ribs on their peripheries, an upper series of such rollers having their ribs in mesh with those on the lower rollers, an endless belt whose upper reach is interposed between the upper and lower series of rollers, drums at the opposite ends of the machine around which said belt passes, means for driving one of said drums, means for yieldably forcing the upper series of rollers downwardly, a swiftly rotating separating roller above the delivery end of the upper reach of the belt, and means for yieldably forcing said separating roller toward this reach, the width of the ribs of the numerous rollers decreasing in the direction of movement of said reach of the belt. 60 65 70 75

In testimony whereof I have hereunto set my hand in presence of two subscribing witnesses.

WILLIAM COOPER.
